COMBINED ROSARY AND STEERING WHEEL

Herbert L. Fast, Dayton, Ohio

Application August 8, 1955, Serial No. 37,351

Term of patent 14 years

(Cl. D14—30)

FIG. 1

FIG. 2

FIG. 3

FIG. 4

Figure 1 is a plan view of a combined rosary and steering wheel embodying my new design.

Figure 2 is a section line 2—2 of Figure 1.

Figure 3 is a section line 3—3 of Figure 1.

Figure 4 is a perspective view.

The essential features of my design reside in those portions shown in full lines.

I claim:

The ornamental design for a combined rosary and steering wheel, as shown and described.
